UNITED STATES PATENT OFFICE.

ARTHUR L. SMITH, OF MELROSE, MASSACHUSETTS.

COLUMN-CAP.

1,324,076.

Specification of Letters Patent.

Patented Dec. 9, 1919.

Application filed May 27, 1919. Serial No. 300,080.

To all whom it may concern:

Be it known that I, ARTHUR L. SMITH, a citizen of the United States, and resident of Melrose, in the county of Middlesex and

5 State of Massachusetts, have invented new and useful Improvements in Column-Caps, of which the following is a specification.

This invention relates to a column cap and particularly to a cap which may be 10 formed from standard structural shapes and adapted for use with tubular steel columns. An object of the invention is to provide a cap for a tubular column which may be easily constructed and readily installed, 15 which can not become displaced transversely of the column, and which has portions extending laterally from the column of sufficient strength to carry loads applied solely thereto instead of to the central portion in 20 alinement with the column.

Referring to the drawings which show certain embodiments of my invention,

Figure 1 is a front elevation of one embodiment of my invention, showing a column cap constructed from angle iron;

Fig. 2 is a side elevation of the cap shown in Fig. 1;

Fig. 3 is a top plan of the embodiment of Fig. 1;

30 Fig. 4 is a top plan of another embodiment of my invention, showing a column cap constructed from T iron;

Fig. 5 is a front elevation of the embodiment of Fig. 4;

35 Fig. 6 is a side elevation of the embodiment of Fig. 4;

Fig. 7 is a front elevation of a further embodiment of my invention, showing a modified form of column cap constructed 40 from angle iron;

Fig. 8 is a side elevation of the embodiment of Fig. 7; and

Fig. 9 is a bottom plan of the embodiment of Fig. 7.

45 Heretofore it has been common practice to provide tubular steel columns with caps formed from substantially flat plates, anchored to the column by bolts embedded in the concrete which fills the column. This

50 construction has not given entire satisfaction for the reason that the plate does not grip the top of the column sufficiently to prevent the column from slipping sidewise from under the cap. It has been proposed to use 55 channel iron for the cap, with the flanges of the channel turned downwardly, but with

such construction slipping is prevented only in a direction transverse of the flanges. It is the purpose of this invention so to construct the cap and so to fit it to the column 60 that the cap is held securely to the top of the column in such manner that the cap and column can not slip relatively to each other in any direction.

In Figs. 1, 2 and 3 I have shown the 65 upper end of a steel tubular column at 1. The column is provided at 2 with slots extending axially of the column through the wall of the tube, diametrically opposite each other. Resting on the top of the column is a 70 T-shaped cap 3 comprising two sections of angle iron 4 positioned with two of their flanges 5 back to back and inserted in the slots 2 and with their remaining flanges in alinement. The abutting flanges are secured 75 together by rivets 6 or other suitable means and have their corners cut off diagonally as shown at 7. The rivets 6 are preferably so positioned through the flanges that their heads abut the outside surface of the tubular 80 column, thus positioning the flanges 5 of the cap in the slots of the tube so that the cap and column are locked against lateral movement relatively to each other in the direction of the flanges. To secure the cap to the top 85 of the column anchor rods 8 are provided with their heads 9 countersunk in suitable holes in the cap 3. The rods may be secured to the cap 3 in any other suitable manner as by riveting, bolting or welding. These 90 anchors may be rods, bolts, or bars of any shape and are anchored to the column when the column is filled with concrete. The cap 3 is further provided with holes 10 for the purpose of receiving bolts to attach the cap to 95 the base of another column or to any other portion of the structure in which the column is employed.

In Figs. 4, 5 and 6, I have disclosed a modified form of column cap 3 formed from 100 T iron 11, with its flange 12 engaged in the slots 2 in the end of column 1. The cap is in all respects similar to the cap shown in Figs. 1, 2 and 3 except in that no rivets are employed inasmuch as the cap 105 is formed of a single integral piece.

A still further embodiment of my invention is illustrated in Figs. 7, 8 and 9 in which the upper end of the column is formed with pairs of slots 2 and 13, cut at 110 right angles to each other. The cap 3 comprises two pieces of angle iron 4 positioned,

as in Fig. 2 with their flanges 5 secured together by rivets 6, the flanges 5 fitting into the slots 2 of the column. Secured by their legs 15 to the flanges 5 by rivets 14, are angle 5 braces 16, said braces being attached with their legs 17 abutting and secured together by rivets 18. The legs 17 extend outwardly to the edges of the angle irons 4 and are adapted to fit into the slots 13 of the column 10 1. The legs 15 are shorter than legs 17 and engage the inner surface of the column 1 adjacent the slots as shown at 19 in Fig. 9, these braces serving to center the cap relatively to the column in all directions. If 15 desirable a flat steel plate may be secured to the upper surface of cap 3 of sufficient size to cover the entire surface of the cap. Bolt holes for securing the cap to other structural members have been omitted from 20 these figures, but it is to be understood that they could be supplied if the nature of the structure demanded them. It is to be noted that no anchor rods are employed with the embodiment of Figs. 7, 8 and 9 for 25 the reason that the employment of the auxiliary braces 16, very securely holds the cap on the top of the column. Such anchors could be employed however in the manner disclosed in Figs. 1 to 6, if desired.

30 While I have elected to show my improved column cap attached to the top of a tubular column, it is evident that it could also be used as a column base by inverting it and erecting the column upon it.

35 I claim:

1. In a device of the class described the combination of a column provided with an axial slot, a T-shaped cap on the end of said column, said cap comprising two angle 40 irons positioned with certain of their flanges abutting and their other flanges in alignment, the said abutting flanges fitted in said slot.
2. In a device of the class described, the 45 combination of a column provided with an axial slot, a T-shaped cap on the end of said column, said cap comprising two angle irons positioned with certain of their flanges abutting and their other flanges in alignment, the said abutting flanges engaging in 50

said slot, rivets for securing said abutting flanges together, said rivets being so positioned that the said flanges are restrained from endwise movement in said slot.

3. In a device of the class described, the 55 combination of a column provided with axial slots, a T shaped cap on the end of said column, said cap comprising two angle irons positioned with certain of their flanges abutting and their other flanges in alignment, 60 the abutting flanges being secured together and engaging in one of said slots, angle braces secured on either side of said abutting flanges with their adjacent legs secured together and engaging in the other slot. 65

4. In a device of the class described, the combination of a column provided with axial slots, a T-shaped cap on the end of said column, said cap comprising two angle 70 irons positioned with certain of their flanges abutting and their other flanges in alignment, the abutting flanges being secured together and engaging in one of said slots, T-shaped members secured on opposite sides of said abutting flanges with the stems of 75 said T-shaped members in alignment and engaging in the other slot.

5. In a device of the class described, the combination of a column provided with axial slots, a T-shaped cap on the end of said 80 column with the upright of the T engaging in one of said slots, and angle braces secured on either side of said upright with their adjacent legs secured together and engaging in the other of said slots. 85

6. In a device of the class described, the combination of a column provided with axial slots, a T-shaped cap on the end of said column with the upright of the T 90 engaging in one of said slots, angle braces each having one short and one long leg, secured by their short legs on either side of said upright with their adjacent long legs secured together and engaging in the other 95 slot, the short legs of said braces lying entirely within the tube.

Signed by me at Boston, Massachusetts, this fourteenth day of May, 1919.

ARTHUR L. SMITH.
